UNITED STATES PATENT OFFICE.

LOUIS W. RICE, OF NEW YORK, N. Y.

DESIGN FOR A LAMP-SHADE.

No. 39,373.

Specification for Design.

Patented June 23, 1908.

Application filed April 8, 1908. Serial No. 425,952. Term of patent 7 years.

To all whom it may concern:

Be it known that I, LOUIS W. RICE, a citizen of the United States of America, residing at New York, in the borough of Manhattan, county and State of New York, have invented a new, original, and ornamental Design for Lamp-Shades, of which the following is a specification, reference being had to the accompanying drawing, forming part thereof.

The figure represents a side-elevation of a lamp-shade showing my design.

I claim:

The ornamental design for a lamp-shade, as shown.

LOUIS W. RICE.
